United States Patent Office.

GEORGE P. FARMER, OF PHILADELPHIA, PENNSYLVANIA.

Design No. 3,052, dated May 26, 1863.

DESIGN FOR A TRADE-MARK.

The Schedule referred to in these Letters Patent and making part of the same.

TO ALL WHOM IT MAY CONCERN:

Be it known that I, GEORGE P. FARMER, of the city and county of Philadelphia, State of Pennsylvania, have invented or produced a new and original Design for a Trade-Mark; and I do hereby declare that the accompanying drawing, and the following explanation thereof, form a full, clear, and exact description of the said design.

The drawing represents a view of my design for a trade-mark, which has in the centre the figure of a fish, over the top of which are the words "hand-laid," and beneath the same the word "lines," while across the body of the fish are the words "trade-mark."

I claim the design for a trade-mark, substantially as described, and represented in and by the accompanying drawing.

In testimony whereof, I have signed my name to this specification in the presence of two subscribing witnesses.

GEORGE P. FARMER.
